UNITED STATES PATENT OFFICE

EARL P. SMITH, OF BRIGHTON, BOSTON, MASSACHUSETTS

HAND STAMP

Application filed October 8, 1927. Serial No. 224,874.

This invention relates to printing devices and particularly to mechanisms of this character which are known as hand stamps. These stamps are provided with movable heads carrying certain printing or symbol impressing elements which may be controlled manually and/or automatically to change the arrangement of symbols impressed by the stamp. Devices of this character are commonly used in numbering and dating receipts, stock certificates, tickets, bank documents, baggage checks, work slips in factories and for numerous other purposes.

The present invention is designed to provide various structural improvements in stamps of this character and is particularly intended to prevent dishonest or fraudulent use of the stamping device. Thus suitable locking or sealing means are provided to prevent unauthorized setting or resetting of the symbol-impressing elements or unauthorized tampering with the register which may indicate the numbers printed by the stamp. For example, locking means of this character may prevent the duplicate numbering or incorrect dating of stock certificates, receipts, or checks of various sorts.

Many stamps of this character are provided with mechanism for automatically changing the arrangement of the printing elements so that the symbols impressed by the stamp may be changed in succession. For example, machines of this character may be arranged to print successive numbers in duplicate or to imprint any series of symbols in a predetermined order. Ofttimes in conjunction with such a numbering mechanism a counter or register is provided which indicates exteriorly of the device the particular arrangement of printing elements within the head so that the user of the device will know exactly what will be printed by the head when it is brought down into juxtaposition to the platen. In conjunction with such automatic numbering or printing mechanism, stamps of this character are also provided with manually controllable stamping mechanism which may be adjusted from time to time to indicate the date, etc. The present invention is designed to effect the locking or

sealing of the automatic mechanism for controlling the numbering means or the like so that this mechanism can not be disturbed without knowledge upon the part of the head of the establishment. The invention furthermore provides locking means so that unauthorized tampering with the manual control for the date stamp or the like may be prevented. Thus the key for this locking means may be kept by the head of the establishment and the dating stamp changed by him each day and locked in its adjusted position so that unauthorized dating back or dating ahead can not be effected by the stamp.

The above and further objects and advantageous features of the invention will be apparent to those skilled in the art upon a reading of the subjoined description and claims in conjunction with the accompanying drawings, in which:

Fig. 1 is a side elevational view of the improved stamping device;

Fig. 2 is an elevational detail of the opposite side of the device;

Fig. 3 is an elevational detail of the slot guard upon the interior of the stamping head;

Fig. 4 is a side elevation of the stamping head;

Fig. 5 is a section on line 5—5 of Fig. 4;

Fig. 6 is a sectional detail of a portion of the stamping head taken on line 6—6 of Fig. 1;

Fig. 7 is a sectional view of a portion of the head particularly illustrating the mechanism for automatically controlling the numbering means; and

Fig. 8 is a perspective detail of part of the same.

The type of stamping device exemplified by the accompanying drawings comprises a base portion 1 designed to rest upon a table, desk, counter or the like. This support carries the arm 2 pivotally secured to one end thereof while the stamping head 3 is mounted upon the outer end of arm 2, a handle 4 being provided for the convenient manipulation of the arm. A suitable spring 6 is arranged under compression normally to force the head 3 upwardly out of engagement with the

platens 54 which is located upon base member 1. The head preferably contains suitable numbering mechanism which may be arranged to print successive numbers in duplicate or in any other desired manner.

In order to control the numbering mechanism, I provide a lever 66 pivotally connected to a fixed part of the machine such as the base 1 by a pivot element 8 and a bracket 9, the latter preferably being secured to the base by non-detachable fastenings, such as rivets 70. Relative movement between the lever 66 and the head serves automatically to adjust the numbering means. Mechanism for this purpose is more particularly illustrated in Figs. 7 and 8, which show the end of lever 66 provided with a depending lug 7 adapted to engage notches on the control wheel 10 that is connected to the rolls 71 carrying the number impressing elements; for example, the wheel 10 may be secured to the adjoining roll 72 to rotate therewith. Each of the adjoining numbering rolls 71 may be connected to the first roll by any suitable mechanism of the type conventionally employed in odometers, numbering machines, or the like, which is effective in causing the movement of each roll for one-tenth of its peripheral extent for every ten similar movements of the adjoining roll. Since the details of mechanism of this character form no part of the present invention and since the same is conventional in all numbering machines, I have not shown the same in detail in the accompanying drawings. An arm upon lever 66 carries a roller 11 which engages the finger 12 upon an oscillating locking member 13 that is pivotally mounted on the interior of the head, as designated by numeral 14. Locking member 13 is also provided with downwardly projecting extensions 16, each of which normally engages one of the depressions upon the periphery of digit wheels 72, each of which are secured to a corresponding roll 71. Springs 17 and 18 tend to urge the fingers 7 and 16 into engagement with the depressions upon the peripheries of the wheels 10 and 72. The downward movement of the head causes the lever 66 to move upward in slot 19 in the rear wall of the head. This relative movement of lever 66 and head 3 causes the roller 11 to move member 13 and projections 16 upwardly away from wheels 72, and at the same time causes the wheel 10 to be turned when the head moves back toward its normal upper position. The intermediate portion of the lever 66 preferably is articulated to the downwardly extending link 20 which extends into a hollow portion of base 1 to operate the registering or counting mechanism 69 that indicates the relative position of the number-impressing elements in stamping head 3. This mechanism may be visible through a window arranged in the top of the support 1.

It is to be understood that the link 20 has

a very restricted movement and accordingly that the lever 66 remains substantially stationary, the movement of the head during each stamping action causing relative movement between the lug 7 and the control wheel 10. Thus due to the tapered shape of lug 7 during downward movement of the head the lug will move upwardly away from the notch with which it has been engaged and at the end of the downward stroke of the head will lift the locking member 13 away from the wheels 72. At the beginning of the upward movement of the head the lug 7 will be positioned to engage an adjoining notch in the wheel 10 and to turn the same to bring another digit into symbol impressing position, the locking member 13 again dropping into place to hold the walls 72 in position to prevent movement of the same until the next stamping stroke is substantially completed.

A plurality of manually controllable, symbol-impressing elements are also arranged upon a series of wheels within the head 3. These wheels are controllable by a plurality of wheels located upon the exterior of the head, and designated in general by numeral 25. Thus, for example, the outer control wheel 26 may be movable to indicate the year, the intermediate wheel 27 may be movable to indicate the day of the month, and the inner wheel 28 may be movable to indicate the month. Suitable concentric spindles connect the control wheels 26, 27 and 28 with the conventional symbol-impressing elements.

In order to avoid unauthorized tampering with the manual control wheels, I provide locking means designated in general by numeral 30, and comprising a conventional lock 31 which may be controlled by a key of the usual type. The slide bolt of the lock, however, is of special form, being provided with a transverse extension 33 having three arms 34 projecting outwardly therefrom in the planes of wheels 26, 27 and 28 respectively. Suitable openings 35 to be engaged by bolt extensions 34 are provided in the peripheries of the wheels to correspond to the adjusted positions of the same. Thus, when the mechanism 31 is in its locked condition pins 34 engage openings 35 in each of the manual control wheels, while, when the mechanism is in its unlocked condition, the bolt is retracted and the wheels are released to permit their ready adjustment.

In order to prevent unauthorized tampering with the mechanism within the stamping head 3 and particularly the number-control mechanism, I provide a guard 40 for the slot 19 which accommodates the lever 66. This guard preferably is in the form of a box-like sheet metal member having an opening 41 large enough to permit the lever 66 to extend therethrough. The guard is slidably mounted in U-shaped brackets 43 which are secured to the interior of the head by fasten-

ing means 44. In this connection it is to be noted that the various portions of the head are held in place by fastening means 67 upon the inside thereof so that it is impossible for an unauthorized person to disassemble the head.

In order to afford access to the interior of the head, I provide a closure member 45 which may comprise one side of the head and 10 has inwardly projecting ears 46 to engage a pintle member 47, whereby the downward swinging of the closure member may be permitted.

I provide the lock 50 which may be of any 15 convenient form but preferably is of the conventional lead seal type with distinctive markings, having a short wire 51 passing through aligned ears 52 and 53 upon the head and the closure member respectively, in 20 order to hold the closure member firmly in engagement with the head. Thus it would be necessary to break the seal in order to obtain access to the interior of the head, so that it would at once be noticed if there 25 was unauthorized tampering with the mechanism within the head.

Preferably the ribbon rolls are located exteriorly of the body portion of the head and access thereto is afforded by the swinging 30 closure elements or tape containers 49 which may be manipulated to permit movement of the ribbon or replacement of the same without necessitating access to the interior of the head.

35 I provide a suitable closure member or door 60 for the counter mechanism 69 in the base 1. This door is provided with a locking or sealing element 62 (Fig. 2) similar to member 50.

40 It is evident that provision of the various locking means described above prevents unauthorized adjustment of either the numbering or the dating mechanism, the locking means for the manual control mechanism being 45 however designed to permit adjustment of such mechanism by authorized persons while the locking means for the numbering and registering mechanism would immediately indicate tampering, so that it will at 50 once be obvious if anybody has had access to the same. While I have shown metal seals for the closure members in the head and base of the machine, it is obvious that any suitable means controllable by a key or dial 55 lock or the like might be substituted for the sealing elements if desired, and I intend the term "locking means" as used in the foregoing claims, to cover a suitable seal as well as mechanically operable locking means.

60 I claim:

1. In a machine for successively stamping a series of symbols in a predetermined order, which comprises a movable head carrying symbol-impressing elements, means within 65 the head, for varying the arrangement of

the impressing elements, means for locking the head to prevent access to the interior thereof, a part extending into the head from a fixed part of the machine automatically to change the arrangement of the impressing elements in response to movements of the head, said head having an opening to permit the movement of said member relative to the head, and a guard over the opening.

2. In a machine for successively stamping a series of symbols in a predetermined order which comprises a movable head carrying symbol-impressing elements, means within the head for varying the arrangement of the impressing elements, a part extending into the head from a fixed part of the machine automatically to change the arrangement of the impressing elements in response to movements of the head, said head having an opening to permit the movement of said member relative to the head, and a movable guard over the opening, said guard comprising a sheet metal housing slidably mounted upon the inside of said head.

3. In a machine of the class described, which comprises a stamping head carrying a series of symbol-impressing elements, certain of said elements being movable to impressing position, means for changing the position of the impressing elements, means for locking this means against movement to prevent unauthorized change in the position of the symbols, said locking means comprising a bolt slidably mounted to engage the means in a plurality of positions which correspond to its positions for printing symbols in different combinations.

4. A machine for successively stamping a series of symbols in a predetermined order comprising a movable head, symbol-impressing elements carried by said head, mechanism responsive to successive movements of said head for automatically changing the relation of the symbol-impressing elements, a portion of said mechanism within the head being adjustable to vary the arrangement of the impressing elements, a closure upon the head locking said portion against unauthorized tampering, tape containers upon the outside of the head, closures for said containers movable independently of said closure upon the head, whereby the tape may be reached without necessitating access to the interior of the head.

5. In a machine for stamping a series of symbols in a predetermined order, a fixed support, a movable head carried by the support, symbol-impressing elements carried by the head, mechanism responsive to successive movements of the head in relation to the fixed support for automatically changing the relation of the symbol-impressing elements, a portion of said mechanism comprising a member extending into the head and con-

5 nected to the fixed support, and means for locking said head to prevent unauthorized tampering with the mechanism therein, said member which extends through an opening in the head being movable in relation thereto as the head is moved, and a guard associated with said opening to prevent unauthorized access to the interior of the head through said opening.

10 6. In a machine for stamping a series of symbols in a predetermined order, a fixed support, a movable head carried by the support, symbol-impressing elements carried by the head, mechanism responsive to successive movements of the head in relation to the fixed support for automatically changing the relation of the symbol-impressing elements, a portion of said mechanism comprising a member extending into the head and connected to the fixed support, and means for locking said head to prevent unauthorized tampering with the mechanism therein, said member which extends through an opening in the head being movable in relation thereto as the head is moved, and a guard associated with said opening to prevent unauthorized access to the interior of the head through said opening, said member extending through the guard, and guide means holding the latter in juxtaposition to the opening and permitting its movement with the link.

15 7. A machine for stamping symbols comprising a fixed support, a movable head, linkage connecting the head to a part of the fixed support whereby movement of the head in relation to the latter is effective in causing movement of certain symbol-impressing elements within the head, manually operable means to cause the relative adjustment of other symbol-impressing elements within the head, a closure upon the head, a locking factor associated with the closure and normally preventing unauthorized tampering with the mechanism within the head, and locking means engageable with the manually operable means to prevent unauthorized adjustment of the symbols controlled thereby.

20 8. A machine of the class described comprising a stamping head, a plurality of symbol-impressing elements which are carried by the head and are movable in relation to each other, control members exterior of the head for causing the relative movement of certain of said impressing elements to any one of a plurality of selected positions to vary the relative positions of the elements, and key operated locking means to prevent unauthorized movement of the control members, said locking means being arranged to lock the same against unauthorized tampering in any one of a plurality of selected positions corresponding to the relative positioning of the impressing elements.

25 9. A machine of the class described com-

70 prising a fixed support, a stamping head movable in relation to the support, a plurality of impressing elements carried by said head, a closure upon the head, means normally locking the closure in place to prevent unauthorized tampering with the elements, tape containers upon the outside of the head, closures for said containers movable independently of said closure upon the head whereby the tape may be reached and replaced without necessitating access to the interior of the head.

75 10. A machine for successively stamping a series of symbols, comprising a movable housing, a base for supporting the article to be stamped, a series of impressing elements within the housing, the housing having an opening exposing an element for engagement with an article on the base, means normally holding the housing in operative 80 position spaced from the base, said housing being movable into juxtaposition to the base, mechanism automatically causing movement of the impressing elements in response to such movement of the housing, holding means within the housing normally preventing movement of the impressing elements and automatically releasing the elements only when the housing closely approaches the base, a movable closure forming a part of the 85 housing, locking means holding the closure in closed position against unauthorized tampering, the holding means being manually operable to release the elements and to permit their selective movement when the closure is moved to its open position, whereby unauthorized tampering with the elements is prevented by the locked closure and by the holding means which automatically releases the elements only when the opening in the 90 closure is closely adjacent to the base.

105 11. A stamping machine comprising a fixed support, a movable head carried thereby, a plurality of movable wheels enclosed by the head, symbol impressing elements carried by the wheels, the head having an opening exposing an element to stamp an article upon the fixed support, mechanism for varying the relative positions of the wheels and elements, said mechanism being automatically operable in response to movement of the head toward a printing position in juxtaposition to the support, holding means normally engageable with parts carried by the wheels and locking the latter against relative movement, said holding means being automatically disengageable from said parts only when the head closely approaches the support, a movable closure forming a part of the wall of the head, locking means normally retaining the closure in its closed position to prevent unauthorized tampering with the holding means within the head, the holding means being manually disengagable from the parts carried by the wheels to permit man- 110

ual movement of the symbol impressing elements when access is afforded to the interior of the head by movement of the closure to its open position, whereby unauthorized tampering with the symbol impressing elements is prevented, since the same are held in position by the holding means until the opening in the head is closely juxtaposed to the support or unless authorized access to the interior of the head is permitted by the unlocking of the locking means and the movement of the closure to open position.

Signed by me at Boston, Massachusetts this 27th day of September, 1927.

EARL P. SMITH.
